(57) **CLAIM**

I claim the ornamental design for pair of protective breast and nipple covers for protection while tanning, as shown and described.

DESCRIPTION

FIG. 1 is a front view of a right side protective breast and nipple cover with a glossy surface;

FIG. 2 is a rear view of the right side protective breast and nipple cover with a non-reflective surface;

FIG. 3 is a top view of the right side protective breast and nipple cover shown in FIG. 1 (the bottom view being a mirror image of the top view);

FIG. 4 is a left side view of the right side protective breast and nipple cover shown in FIG. 1;

FIG. 5 is a right side view of the right side protective breast and nipple cover shown in FIG. 1;

FIG. 6 is a front view of a left side protective breast and nipple cover with a glossy surface;

FIG. 7 is a rear view of the left side protective breast and nipple cover with a non-reflective surface;

FIG. 8 is a top view of the left side protective breast and nipple cover shown in FIG. 6 (the bottom view being a mirror image of the top view);

FIG. 9 is a right side view of the left side protective breast and nipple cover shown in FIG. 6;

FIG. 10 is a left side view of the left side protective breast and nipple cover shown in FIG. 6; and,

FIG. 11 is a front elevational view of the pair of protective breast and nipple covers in use, the broken line portion showing the covers in forming no part of the claimed design.
